(57) CLAIM

The ornamental design for a lounge bed, as shown and described.

DESCRIPTION

FIG. 1 is a perspective view showing the lounge bed of the present invention.

FIG. 2 is a top view of the invention shown in FIG. 1.

FIG. 3 is a front view of the invention shown in FIG. 1.

FIG. 4 is a back view of the invention shown in FIG. 1.

FIG. 5 is a first side view of the invention shown in FIG. 1; and,

FIG. 6 is a second side view of the invention shown in FIG. 1.

The broken lines shown in the drawings are for the purpose of illustrating the mattress of the lounge bed and forms no part of the claimed design.

1 Claim, 6 Drawing Sheets
